UNITED STATES PATENT OFFICE

129,923

DESIGN FOR A LIPSTICK APPLICATOR

Irene B. Kaltenbach, Los Angeles, Calif.

Application May 29, 1941, Serial No. 101,226

Term of patent 14 years

To all whom it may concern:

Be it known that I, Irene B. Kaltenbach, a citizen of the United States of America, residing in Los Angeles, in the county of Los Angeles, State of California, have invented a new, original, and ornamental Design for a Lipstick Applicator, of which the following is a specification, reference being had to the accompanying drawing, forming a part thereof.

In the drawing:

applicator showing my new design, with the applicator shown not encased.

I claim:

The ornamental design for a lipstick applicator, as shown.

IRENE B. KALTENBACH.
